DENTAL CHAIR

Boyd E. Parker, Glendale, Calif., assignor to George E. Parker Company, Pasadena, Calif., a partnership

Filed Feb. 3, 1960, Ser. No. 59,257

Term of patent 14 years

(Cl. D15—3)

Fig. 1.

Fig. 2.

Fig. 3.

Fig. 1 is a side perspective view of a dental chair showing my design. The left side is identical to the right except for the omission of the handle or lever seen on the right side.

Figure 2 is a plan view.

Fig. 3 is a front elevational view, the base having been omitted for convenience of illustration.

The back of the chair is plain and unornamented.

The dominant features of my design reside in those portions shown in full line on the drawing.

I claim:

The ornamental design for a dental chair, as shown and described.
